UNITED STATES PATENT OFFICE

1,928,957

SWING JOINT STEEL HOSE

Forrest Joseph Young, Los Angeles, and Demery Ambrose Murphy, Torrance, Calif., assignors to The National Supply Company, Toledo, Ohio, a corporation of Ohio

Application June 29, 1931. Serial No. 547,486

7 Claims. (Cl. 285—18)

This invention relates to swing joint steel hose, and more particularly to swing joints for coupling sections of steel hose together, the steel hose being of the type utilized in the connecting of mud pumps or the like with the hydraulic swivel utilized in the rotary drilling process for conducting the circulating fluid or mud from the mud pump or pumps to the swivel for introduction into the drill pipe and for conveying such mud or circulating fluid from the pump to the rotary swivel under high or relatively high pressures.

In the handling of circulating fluids where the rotary drilling processes are employed, particularly during the drilling of deep wells, great difficulty has been encountered in the maintenance of the fluid conduit connecting the mud pumps with the rotary hydraulic swivel due to the extremely abrasive character and the high pressure of the fluid being handled.

It is, therefore, an object of this invention to provide a swing joint which is constructed in such a manner as to reduce the abrasive action of the circulating fluid under high pressure on the swing couplings utilized in such a conduit and which is applicable for the handling of the abrasive high pressure fluids, and is also a simple and inexpensive construction.

Another object of this invention is to provide a swing joint for a steel hose which includes a yoke member and a swivel member, the yoke member providing a passage between its tines into which the swivel member is adapted to be passed and in which passage the swivel member is adapted to be pivotally supported on a pin retained in position by means of pipe plugs threaded to the tines of the yoke member at the opposite end of the pins, and which swivel member carries packing members which are adapted to be expanded under the fluid pressure of the fluid passing through the joint as assembled.

Other objects and advantages of this invention it is believed will be apparent from the following detailed description of a preferred embodiment thereof as illustrated in the accompanying drawings.

In the drawings:

Figure 1 is an elevation of a swing joint embodying our invention.

Figure 2 is a side elevation of a compound swing joint embodying our invention.

Figure 3 is a side elevation of a compound swing joint embodying our invention wherein the two axes of rotation of the compound swing joint

are positioned at 90 degrees to provide a form of universal swing joint.

Figure 4 is a sectional edge elevation taken substantially on the line 4—4 of Figure 1.

Figure 5 is a side elevation mainly in vertical mid-section of the swing joint illustrated in Figure 1.

In the preferred embodiment of our invention 1 indicates a swivel member provided at its outer end with a threaded branch 2 into which a joint of steel hose 3 is adapted to be threaded. 4 indicates a yoke member having at its outer end a branch 5 into which a section of a steel hose 3 is adapted to be threaded.

In the modification of my invention illustrated in Figure 2, to provide a compound swing joint a double yoke member 6 is provided having swivel heads 7 and 8 at its opposed ends, the swivel heads 7 and 8 being adapted to fit between the tines of yoke members 4 in a manner similar to the modification illustrated in Figure 1. In this modification the two yoke members 4 having threaded branches 5 are employed, and the sections 3 of the steel hose are threaded into the branches 5 of the yoke members 4.

In the modification of our invention illustrated in Figure 3, the construction is the same as illustrated in the modification shown in Figure 2 with the exception that the double swivel member 9 is formed with the swivel heads 10 and 11 rotated through 90 degrees so that the pivotal supports of said swivel heads 10 and 11 are spaced 90 degrees to provide a form of universal swing joint connection for the sections 3 of the steel hose.

In each of the modifications illustrated in Figures 1, 2 and 3 the yoke members 4 and the swivel members 1 are of the same construction except that in the illustrations of Figures 2 and 3 the double yoke members 9 and 10 are provided. Inasmuch as the heads of the yoke members 1, 6 and 9 are of identical construction, it is only deemed necessary to set forth in detail the construction of the simplest of these swing joint members as is illustrated in Figure 1.

The swivel member 1 includes a swivel head 12 formed at the end opposite the threaded branch 2. The head 12 of the swivel member 1 fits between the tines 13 and 14 of the yoke 4 and is pivotally supported in position on a pin 15 which is passed through a transverse bore 16 formed through the tines 13 and 14 of the yoke member 4 and is retained in position by means of pipe plugs 17 and 18 which are threaded into

the ends of the bore 16 in position to engage the ends of the pivot pin 15.

The swivel members 1, 6 and 9 are provided with longitudinal passages 19 which terminate in diverging fluid passages 20 and 21 separated by a central diverting barrier 22.

The diverting barrier 22 is formed as a lip which extends into the passage 19. The diverging branches 20 and 21 of the passage 19 extend from the faces 23 and 24 of the heads 12, 7, 8, 10 and 11 of the yoke members 1, 6 and 9 respectively on opposite sides of the pin bore 25 formed axially through the heads 12, 7, 8, 10 and 11 respectively. The yoke members 4 are formed of two spaced tines 13 and 14 which diverge outwardly from the threaded branch 5 and provide diverging fluid passages 26 and 27 which terminate in annular channels 28 and 29 which pass around the bore 16 of the pin 15 and terminate in the inner faces of the tines 13 and 14 in communication with diverging branches 20 and 21 of the passage 19 formed through the swivel members 1 or 6 or 9 depending upon the form of connection to be formed.

25 The diverging fluid passages 26 and 27 are relatively long and the two diverging fluid passages 26 and 27 diverge or converge upon opposite sides of a central section 30 of the yoke member 4 and are so formed as to bring the two separated passages 26 and 27 together gradually so as to reduce as far as possible the turbulence set up in the flow of the fluid under high pressure through the swing joint provided.

30 The barrier 22 which extends up into the passage 19 of the swivel member 1 is also so positioned and formed as to reduce as far as possible the turbulence created in the fluid passing over such a barrier 22 in the separation, or in the bringing together of the two separated portions 40 of the circulating fluid or liquid which is passing through the swing joint under high pressure.

In these constructions in order to maintain a more uniform flow of the circulating abrasive fluid under high pressure, the pivot pin 15 which 45 connects the swivel members and the yoke members of the joint together is not located at the point of maximum spread of the two branches of the fluid formed in passing through the swing joint, but is positioned in all cases near the end of 50 the yoke member 4 so as to enable the yoke member 4 to be formed with relatively long fluid branches 26 and 27 which are brought together under a slight degree of divergence or convergence, depending upon the direction of flow of the 55 circulating fluid under high pressure.

In order to pack the connection, the faces 23 and 24 of the swivel members 1 are provided with annular packing recesses 31 and 32 into which packing 33 and 34 is positioned.

60 The packing 33 and 34 is preferably of the cup type and fluid passages 35 are cut in the faces 23 and 24 of the swivel member 1 from the diverging branches 20 and 21 of the passage 19 to the annular packing recesses 31 and 32 so that the fluid under pressure acts to expand the packing rings 33 and 34 between the swivel member 1 and the yoke member 4 so that as the pressure of the fluid passing through the swing joint increases, the packing is expanded with greater force by such fluid pressure to maintain a fluid-tight joint.

In order to protect the pin 15 from the abrasive action of the fluid under high pressure passing through the swing joint, similar annular packing recesses 36 are cut in the opposed faces 23 and

24 of the heads of the swivel members and packing rings 37 are fitted in the recesses 36. Fluid passages 38 are formed in the faces 23 and 24 of the diverging passages 20 and 21 to the recesses 36 so that the packing 37, which is preferably of the fluid expansible cup type, is expanded outwardly between the faces 23 and 24 of the swivel members 1 and the inner adjacent faces of the tines 13 and 14 of the yoke member 4 within the interior of the annular passage formed around the pin 15 in the head 12 of the swivel member 1.

80 The pin 15 is lubricated by means of a lubrication fitting 41 which is threaded in a lubrication passage 39 formed in the swivel member 1 in communication with a lubrication pocket 40 surrounding the pin 15.

85 In assembling the swing joint embodying our invention, the swivel member 1, carrying the packing rings 33, 34 and 37, is merely slid between the tines 13 and 14 of the yoke member 4, the pin 15 being then passed through the bores 16 and 25 and is retained in position by means of the pipe plugs 17 and 18 which are threaded to the ends of the bore 16 formed transversely of the 100 tines 13 and 14. As fluid under pressure passes under the swing joint formed, packing 33, 34 and 37 is expanded to maintain the joint fluid tight.

90 Having fully described our invention, it is to be understood that we do not wish to be limited to the details herein set forth, but our invention is of the full scope of the appended claims.

We claim:

1. In a metallic swing joint connection, the combination of a swivel member having a swivel head at one end, said swivel head having parallel spaced faces and having a fluid passage extending therethrough terminating in a pair of diverging branches opening through the parallel spaced faces of the swivel head, a yoke member having a pair of diverging tines having fluid passages opening into the opposed adjacent faces thereof and in communication with the branch openings in the faces of the swivel head, a pin passed through the yoke and swivel members providing a pivot, means to retain said pin in position, means to lubricate said pivotal connection, and means for packing the mating faces of the yoke and swivel members to prevent leakage of fluid conducted therethrough and to maintain the lubricated pivot free of said fluid.

110 2. In a metallic swing joint connection, the combination of a swivel member having a swivel head at one end, said swivel head having parallel spaced faces and having a fluid passage extending therethrough terminating in a pair of diverging branches opening through the parallel spaced faces of the swivel head, a yoke member having a pair of diverging tines having fluid passages opening into the opposed adjacent faces thereof and in communication with the branch openings in the faces of the swivel head, said passages through the faces of said members being positioned between concentric internal and external packing 120 recesses in the mating faces of one of said members, packing mounted in said recesses to seal the joint against leakage both radially inward and outward, a pin passed through the yoke and swivel members providing a pivot, means to retain said pin in position, and means to lubricate 125 said pivotal connection.

130 3. In a metallic swing joint connection, the combination of a swivel member having a swivel head at one end, said swivel head having parallel spaced faces and having a fluid passage ex- 135

CERTIFICATE OF CORRECTION.

Patent No. 1,928,957.

October 3, 1933.

FORREST JOSEPH YOUNG, ET AL.

It is hereby certified that error appears in the printed specification of the above numbered patent requiring correction as follows: Page 3, line 119, claim 7, for "face" read faces; and that the said Letters Patent should be read with this correction therein that the same may conform to the record of the case in the Patent Office.

Signed and sealed this 28th day of November, A. D. 1933.

F. M. Hopkins
